UNITED STATES PATENT OFFICE.

CHARLES YORGER AND DAVID W. WEST, OF INDIANAPOLIS, INDIANA.

STORE-CABINET FOR SALES ACCOUNTS.

SPECIFICATION forming part of Letters Patent No. 634,713, dated October 10, 1899.

Application filed March 20, 1899. Serial No. 709,717. (No model.)

To all whom it may concern:

Be it known that we, CHARLES YORGER and DAVID W. WEST, citizens of the United States, residing at Indianapolis, in the county of Marion and State of Indiana, have invented certain new and useful Improvements in Store-Cabinets for Sales Accounts; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to devices for the use of merchants for facilitating and simplifying business transactions connected with the selling of goods on a credit system; and it consists in a convenient cabinet embodying new and novel elements in the construction thereof whereby billing-forms are retained and on which the names of purchasers are entered in alphabetical order, together with the entries of their purchases at the moment of making the sale, and whereby the bill of any purchaser may be instantly referred to for making subsequent charges or for summing up and rendering statement of account.

Our invention consists, further, in the parts and combination and arrangement of parts embraced in the details of construction, as will be hereinafter described, and pointed out in the claims.

In conducting a retail store much detail work is required, with great possibilities of errors, in keeping the accounts of those to whom credit is given, entailing considerable expense in the keeping of account - books, usually involving the multiplication of entries, all of which is a serious loss to the merchant, particularly in cases where the entries of sales may be inadvertently omitted in crowded hours.

Our object is to provide a simple and convenient means whereby the ordinary billing-forms may be substituted for the usual system of books in making sales entries and rendering the transferring of accounts from book to book unnecessary, so that the original entries stand until liquidated. A further object is to provide equally convenient receptacles wherein the bills as the sheets be-

come filled up and accumulate may be placed so as to be readily accessible when rendering accounts for settlement. These objects are fully attained in our invention, which is, furthermore, of utility in being portable, so that the accounts may be transferred when desired to a safe, and it is cheaply manufactured and durable and economical in use.

Referring to the drawings, Figure 1 represents a perspective view illustrating a cabinet constructed in accordance with our invention and in the position in which it is used; Fig. 2, a front elevation of the same exaggerated and illustrating its position when ready for referring to a particular account; Fig. 3, a central vertical sectional view taken transversely to a side elevation; Fig. 4, a perspective view of the banked hinge-frame; Fig. 5, a fragmentary plan view of a billing-leaf, showing the bill-clip; and Fig. 6, a perspective view of one of the billing-leaves and balancing-springs.

In practically carrying out our invention we construct a cabinet A of convenient size to be portable and suitable to set upon a counter or desk, or it may be provided with legs, preferably connected with a frame separate from the cabinet. Wood is a suitable material for the main parts, while sheet-tin is preferable for the billing-leaves, and steel or brass wire are suitable material from which to form the springs and clips.

The cabinet consists, essentially, of a case having an open front and a drop-leaf B and in which a series of billing-leaves D are hinged and inclosed when not in use; but in order to further enhance the value of our invention we construct the cabinet substantially as shown, which has a greater depth than is required for the billing-leaves alone, and comprises a bottom e, a closed back, sides, and a top d of two parts, the rear part of which is secured to the body of the cabinet, while the front C is of the drop type, having a flange or lip y to cover the upper edge of the leaf B when it is closed and connected by hinges f to the part d. Extending from bottom to top and from the back forward a suitable distance is a partition c, between which and one side are a series of shelves a, set highest at their front edges. These shelves are designed to receive the

bills which may be completed and removed from the billing-leaves and may be suitably indexed, a suitable number of shelves being either thirteen or twenty-six. Between the 5 opposite side of the partition and the opposite side of the cabinet are a suitable number of inclined shelves *b*, designed to temporarily receive pass-books of customers and for storing new books. Forward of the shelves the 10 sides *A'* and bottom of the cabinet extend a suitable distance to receive the billing-leaves and their supporting-frame. A hook *k* and eye *r* afford means for retaining the drop-leaf *B* when closed, and a suitable lock may 15 also be employed.

The billing-leaves *D* are for the purpose of carrying the individual accounts, indexing them sufficiently for convenience, and also for separating them in series, as well as affording a ready table upon which to write. Thirteen, twenty-six, or any desired number 20 of leaves may be employed and each leaf may be of suitable width to receive any convenient number of bill-forms, the cabinet being 25 proportional accordingly. The upper side of the leaf *D* is designated by *h* and the under side by *i* in order to render the description clear. The edge *w* of each leaf is turned downward over a wire *I*, forming a loose 30 hinge-pin, and has a suitable number of notches *w'*, in which are inserted the coils *L* of a spring-clip *E*, bearing upon the upper side *h* and having extensions *l* bearing against the under side *i* of the leaf *D*. At the ends 35 of the hinge-pin are right and left hand coiled springs *J J'*, each having an arm *t* of suitable shape bearing against the under side *i* of a leaf and an arm *u*, suitably anchored, as upon the top *s* of the block *G*, these balance- 40 springs being designed to push the leaves against the front of the shelves, but are sufficiently weak in tension to permit the leaf to rest horizontally when placed in that position. The free edge of the leaf *D* is turned 45 upward and over upon itself, but not tightly, forming a clip *M* for retaining the foot ends of the forms *K*, and the upper side of the clips contain the indexing-letters, as *m*, while the under side of the leaf is provided with 50 corresponding indexing-letters, as *n*.

For the purpose not only of rendering the index-letters visible both when the leaves are up and when down, but to provide ample finger-holds in separating the leaves, the rods *I*, 55 forming the pins upon which the leaves are hinged, are placed in sloping bank position, that for the most forward leaf being lowest and that for the most rearward being highest, the intermediate rods being on a sloping line 60 between. This is accomplished by means of the vertically-disposed plates *F*, which are perforated to receive the rods *I* loosely, the top edges being cut angularly to the bottom *e* of the case, so as to conform to the desired 65 degree of slope, and the perforations and rods are situated so as to conform to the line of the angular upper edge, these plates form-

ing the anchored part of the leaf-hinges and may be secured to the case of the cabinet in any suitable manner; but I preferably support them by means of a connecting-base *H* and back piece *H'*, either formed separately or integrally with the plates *F*, and to the latter are secured blocks *G*, having a sloping top corresponding with the top of the plate, 75 but lower, so as to provide a convenient support for the arms *u* of the balance-springs. Thus a removable frame is provided, which, 80 together with the billing-leaves and accounts, may be quickly withdrawn from the cabinet-case. Suitable latch-bolts *N*, entering recesses *o*, or other suitable latching devices 85 may be employed for retaining the hinge-frame.

In the practical use of our cabinet we place 90 one or more blank bill-heads of the ordinary oblong form under each clip *E* and also under the clip *M* on each billing-leaf *D*. The accounts are then begun by entering the names of debtors on a bill situated according to the index-letter corresponding to the debtor's initial letter. The sales entries are made, and if a pass-book is used the entry is also made therein at the time of sale and no further bookkeeping is required. When a bill 95 becomes full, the amounts are summed up and the total carried to a second blank, while the first is placed in the shelf provided, so that the whole account is instantly accessible without waiting for the posting of books, and when the account is settled the bill is received and delivered to the payer or may be destroyed, thus closing the account. This means is invaluable to the dealer who sells for cash as a rule, but gives occasional credit 100 to a limited number, when extra bookkeeping 105 would be a great inconvenience.

Having thus described our invention, what we claim as new, and desire to secure by Letters Patent, is—

1. A store-cabinet, for sales accounts, comprising upright members provided with a series of horizontal hinge-rods situate in an inclined plane, a series of billing-leaves pivoted to such hinge-rods and each having a series of clips on one surface thereof and the index-letters at the edge thereof opposite the hinge, and springs at such hinges whereby such leaves are retained in vertical positions.

2. A store-cabinet for sales accounts, comprising a case, removable upright members provided with a series of horizontal hinge-rods situate in an inclined plane, a series of billing-leaves all of equal length and pivoted to such hinge-rods and each having a series of clips on one surface thereof and corresponding index-letters on both surfaces at the edge opposite the hinge thereof whereby any particular leaf may be found both when horizontal and when vertical, and springs at such hinges acting against such leaves to partially counterbalance their weight when horizontal.

3. A store-cabinet, for sales accounts, com-

prising a case, a hinge-frame comprising a pair of upright end members provided with a series of horizontal hinge-rods situate in a plane inclined so that the forward one is lower than the rear one of such hinge-rods, a billing-leaf hinged at one edge to each one of such hinge-rods and a coiled spring at an end of each of such hinge-rods and provided each with an arm bearing down upon one of such end members and an arm bearing up against the under side of such connected leaf.

4. A store-cabinet, for sales accounts, comprising a case, a hinge-frame comprising a pair of upright end members provided with a series of hinge-rods situate in a plane inclined so that the forward one is lower than the rear one of such hinge-rods, a billing-leaf hinged at one edge to each one of such hinge-rods, a spring coiled about each one of such hinge-rods and provided with an arm bearing against the under side of one of such connected leaves and an opposing arm suitably anchored.

5. A store-cabinet, for sales accounts, comprising a case, a hinge-frame comprising a base and upright end members provided with a series of hinge-rods situate in a plane inclined so that the forward one is lower than the rear one of such hinge-rods; a billing-leaf 30 hinged at one edge to each one of such hinge-rods and having notches cut in such hinged edge, and provided at the opposite free edge with a clip formed by turning such edge upward and over toward the upper face thereof; clips secured to such hinge-rod in said notches; and coiled springs at the ends of such hinge-rods, one arm of each one of which springs bears against the bottom of one of such billing-leaves and the other arm of which 40 springs bears against the top of such end member.

6. A store-cabinet, for sales accounts, comprising a vertical case, a hinge-frame comprising a pair of upright end members provided with a series of horizontal hinge-rods situate in a plane inclined so that the forward one is lower than the rear one of such hinge-rods, a billing-leaf hinged at one edge to each one of such hinge-rods, a spring 50 coiled about each one of such hinge-rods and provided with an arm bearing against the under side of one of such connected leaves and an opposing arm suitably anchored, corresponding index-letters at both sides of the 55 free edges of such leaves, and shelves in such case at the rear of such hinge-frame.

7. In a store-cabinet for sales accounts, the combination of an upright case provided at the rear portion thereof with a vertical partition 60 extending from the back forwardly and a series of shelves at each side of such partition at the rear portion of such case, the drop-leaf, the sectional hinged top for such case, the hinge-frame situate removably at 65 the lower front of such shelves, the leaves hinged to such hinge-frame, the coiled springs on such hinge-frame, and a latch whereby

such hinge-frame is retained in such case, substantially as set forth.

8. In a store-cabinet for sales accounts, the combination of the hinge-frame comprising a base and a pair of upright end members having inclined top edges and a series of hinge-pins arranged horizontally but in a plane inclined to correspond with said top edges, the 75 notched billing-leaves, the spring-clips, and the springs coiled about said hinge-pins and bearing against the under side of such leaves and upon the top of such end members, substantially as set forth.

9. In a store-cabinet, the combination of a case, a hinge-frame comprising a removable base and counterpart upright end members provided with a series of hinge-rods set horizontally in an inclined plane, a billing-leaf 85 comprising a rectangular form having one edge turned over to form a clip and provided with index-letters and hinged at the edge opposite the turned-over edge to such hinge-rods, clips at such hinge edge, and springs at 90 such hinges whereby such leaves are elastically retained in their vertical positions, substantially as set forth.

10. In a store-cabinet, for sales accounts, the combination of the case having a bottom 95 and a drop-leaf hinged thereto, the hinge-frame comprising a base and a pair of upright end members provided with a series of horizontally-disposed hinge-pins situate in a plane inclined so that the forward one is lower than 100 the rear one of said pins, the billing-leaves pivoted to said hinge-rods, the spring coiled about each one of said pins and having an arm bearing against the under side of one of said leaves and an arm bearing against the 105 top of one of such end members, and a latch whereby said hinge-frame may be detachably retained in said case, substantially as set forth.

11. In a store-cabinet, the combination of 110 the case, the hinge-pins, and the billing-leaves each consisting of a rectangular plate having a series of notches at one edge and turned over one of said hinge-pins and provided at its opposite edge with a clip formed 115 by turning said edge up and over toward the body of said leaf, and the clips in said notches each composed of a continuous piece of wire coiled about said hinge-pin and having a loop bearing upon the upper face of said leaf and 120 ends bearing against the under or reverse side of said leaf, substantially as set forth.

12. In a store-cabinet for sales accounts, the combination of the case A provided with the shelves a and b and partition c and having 125 the forwardly-extending sides, hinged sectional top and drop-leaf; the hinge-frame comprising the base H, ends F, F, blocks G, G, and series of rods I; the billing-leaves D having the clips M and the notches w' at the 130 opposite edge and hinged to said rods; the clips E having the coil L in said notches and around said rods; and the springs J, J', at the ends of said rods and bearing against

4
said blocks and against the under side of said leaves, substantially as and for the purposes set forth.

13. In a store-cabinet, for sales accounts, the combination of the case A provided with the shelves *a* and *b* and partition *c* and having the forwardly-extending sides, the top *d* having the hinged drop-section C, and the hinged leaf B; the hinge-frame comprising the upright end members, and the series of rods I supported by such end members; the billing-leaves D having the notches *w* and hinged to said rods; the clips at the free edge of said leaves; the clips E having the coil L in said notches and around said rods; and the springs J, J' at the ends of said rods, substantially as shown and described.

14. In a cabinet, the combination of the

hinge-frame, the hinge-rods forming part of such hinge-frame, the leaves pivoted to such hinge-rods and having the notches in the hinged edge thereof, the clips in such notches and mounted on said rods, the clip formed integrally by turning over the free edge of each of such leaves and having the index-letters thereon, and the index-letters at the opposite side of such leaves, substantially as set forth.
